ABSTRACT OF THE DISCLOSURE

In a system for cooling a heat-dissipating load by means of a cryogenic fluid passed through a transfer conduit to the load in the form of a two-phase liquid/gas mixture, frost or ice formation on the conduit is inhibited by shrouding the conduit with a stream of dry gas exhausted from the load.

Field of the invention

This invention relates to cooling systems employing a cryogenic fluid as coolant, and in particular to such systems in which the cryogenic fluid is supplied to a region to be cooled as a two-phase mixture of liquid and gas.

Description of the prior art

In some applications, such as when cooling infra-red detectors used with aerial reconnaissance and guidance systems, the required flow rate of coolant is less than that which is readily obtainable from a continuous stream of cryogenic liquid. It has been proposed to employ a two-phase mixture of liquid and gas as coolant to achieve the required low flow rate. The two-phase mixture is produced by passing cryogenic liquid from a source to a region to be cooled along a transfer conduit which is exposed to the surrounding atmosphere to permit heat to flow into the conduit so as to vapourise part of the cryogenic mixture and produce a gas stream in which globules of cryogenic liquid are suspended.

Such a two-phase cooling system functions satisfactorily for short periods of time but it has been found on prolonged runs that the system suffers from the disadvantage that moisture from the surrounding atmosphere condenses on the conduit, particularly on that part of the conduit adjacent the cryogenic liquid source, leading to the formation of frost or ice on the conduit and forming a thermally-insulating layer which interferes with, and ultimately stops, the vapourisation of the liquid to form the gas phase.

Summary of the invention

The formation of frost or ice on the surface of a transfer conduit carrying a two-phase (liquid/gas) mixture of a cryogenic fluid is inhibited by shrouding the conduit with a stream of dry gas from the load being cooled.

Accordingly the present invention provides a cooling system employing a cryogenic fluid which, in its broadest aspect, is as defined in the appended claims.

According to another aspect of the present invention there is provided a method of cooling a region to be cooled which, in its broadest aspect, is as defined in the appended claims.

An embodiment of the invention will now be described by way of example with reference to the accompanying drawing which shows a side elevation, in section, of a diagrammatic cooling system of the invention and as used for cooling an infra-red detector.

Referring to the drawing, the cooling system shown 70 comprises a container 1 of liquid nitrogen, a transfer conduit 3 having a spaced outer jacket 5, and a valve 7

2

(shown on an enlarged scale) through which the container 1 may be filled and by which the container may be pressurised to force liquid nitrogen 9 along the transfer conduit 3 to an infra-red detector shown diagrammatically at 11.

The valve 7 comprises a lower compartment 13, a middle compartment 15 and an upper compartment 16 which are axially aligned. The lower compartment 13 has an axial inlet port 17 to which a nitrogen supply line (not shown) may be coupled, and a radial outlet port 19 connected by a delivery conduit 21 to the lower part of the container 1. The middle compartment 15 has a radial outlet port 27, and it is able to be placed in communication with compartment 16 by movement of a valve member 42 cooperating with a valve seat 41. Compartment 16 has an inlet port 23 connected by a conduit 25 to the gas-filled space 26 above the liquid nitrogen 9 in container 1.

The inlet port 17 and the outer port 19 of the lower compartment 13 are separated by a valve seat 29 having a central aperture 30 through which extends an actuating member 31 having an enlarged diameter part 33 projecting into the inlet port 17. A valve element 35 surrounds and is an easy fit on, the actuating member 31 and is biassed towards the valve seat 29 by a resilient bellows unit 37 attached at one end to the stem of actuating member 31.

The actuating member extends into the middle compartment 15 through a central aperture 38 in the wall 39 separating the two compartments, and is a sliding fit within the aperture 38. The valve seat 41 separates the inlet 23 from the outlet port 27. In compartment 16 is a valve element 42 which is movable with member 31, which is biassed downwardly as viewed in the drawing by a spring 43. That part of member 31 which extends into the compartment 15 is coupled to the wall 39 by a second bellows unit 45 to provide a gas-tight seal between compartments 13 and 15.

A recess 46 formed in the upper wall of the compartment 16 communicates with a pressure-relief valve 47 and a pressure gauge 48 and is isolated from the compartment 16 by the valve element 42 which seats against the upper wall of the compartment when the actuating member 31 is moved to its fully-raised position.

As previously described the valve 7 is connected to the container 1 by the conduits 21 and 25. In the drawing the container 1 is shown partially filled with liquid nitrogen 9, and has an outer vacuum-insulated vessel 51. The transfer conduit 3 extends from the base of the container 1 out through the container and outer vessel 51 to the infra-red detector 11. Between the outer vessel 51 and the detector 11, the transfer conduit 3 is surrounded by a jacket 5, the jacket adjacent the outer vessel 51 having an enlarged end portion 6 which accommodates the curved portion of the conduit 3. The jacket 5 is connected to the neck of the detector 11 and provides a return path for gas from the detector 11, the gas flowing through the jacket 5, a tube 53 connected to the jacket, and to the atmosphere through a control valve 55.

To achieve a two-phase flow of coolant, the internal diameter of the transfer conduit 3 is preferably between $\frac{1}{16}$ inch and $\frac{5}{16}$ inch. If the internal diameter is less than about $\frac{1}{16}$ inch it has been found that the liquid nitrogen is completely vaporised in passing along the conduit, while if the internal diameter is greater than $\frac{5}{16}$ inch the globules tend to deposit from the stream and interrupt the two-phase flow. In the described embodiment, the generally-horizontal part of the transfer conduit 3 extending between the end portion 6 of the jacket 5 and the detector 11 was formed from polyvinylchloride tubing, while the remainder of the conduit was formed from stainless steel tubing. A suitable length for the transfer conduit was 6-12 feet. Other suitable materials may be used for form-

ing the transfer conduit 3, but to achieve two-phase flow a smooth bore is required.

To charge the container 1 with liquid nitrogen, a coupling (not shown) from a reservoir of liquid nitrogen is connected to the inlet port 17. In so doing the coupling contacts the actuating member 31 and moves it against the bias of spring 43 so that when the coupling is fully engaged, the actuating member 31 is in a fully-raised position with valve elements 35 and 42 lifted from valve seats 29 and 41 respectively, and with valve element 42 in contact with the upper wall of compartment 16 to isolate the remainder of this compartment from recess 46. Liquid nitrogen is then fed through the inlet port 17, outlet port 19, and delivery conduit 21 to the container 1, displaced gas being vented to atmosphere from the top of container 1 through the conduit 25, inlet port 23 and outlet port 27. When sufficient liquid has been fed to the container 1, the coupling is disconnected from the inlet port 17, during which operation the actuating member is returned to the position shown in the drawing by the action of spring 43, thereby isolating the conduit 21 from the inlet port 17; isolating conduit 25 from the outlet port 27, and connecting conduit 25 to the vent valve 47 and pressure gauge 48.

The vent valve 47 is arranged to open at a pressure with the range of 1-3 p.s.i.g., which is the pressure required for forcing nitrogen as a two-phase mixture along the conduit 3. This pressure will be quickly reached after filling the container 1, and the cooling operation is begun by opening the flow control valve 55 by the required amount.

When the cooling system is operating liquid nitrogen is passed into the transfer conduit 3 under the pressure applied to the surface of the liquid nitrogen 9 in the container 1. In the portion of the conduit 3 surrounded by the jacket 5 part of the liquid is vaporised by heat passing through the conduit wall from the surrounding atmosphere to produce a two-phase mixture of liquid and gas. The two-phase mixture is delivered to the infra-red detector 11 which is thereby cooled to liquid nitrogen temperatures. In detector 11 virtually the whole of the liquid phase is converted to the gas phase, and the gas phase from the detector 11 is fed through the jacket 5 to atmosphere via the flow control valve 55. The flow rate of the two-phase coolant is adjusted by the valve 55, a suitable rate being 750 cc./min. nitrogen gas to cool an infra-red detector of 0.5 watt load to the temperature of liquid nitrogen.

It will be seen that because the gas which shrouds the conduit 3 is obtained solely from the liquid nitrogen, a moisture-free atmosphere surrounds the conduit 3, and frost or ice formation on the conduit is thereby avoided. It has been found that the temperature difference between the shrouding gas obtained from the detector 11 and the conduit is sufficient for there to be sufficient heat transmitted through the wall of the conduit to maintain the flow of coolant in its two-phase state. Using a 3.5 litre liquid nitrogen container, the cooling system has been

fund to operate satisfactorily for periods of up to 16 hours.

It will be apparent that, depending upon the application, cryogenic liquids other than liquid nitrogen may be employed as the source of coolant, for example liquid oxygen, liquid argon and liquid hydrogen.

We claim:

1. A cooling system employing a cryogenic fluid, including a thermally-insulated container for liquid cryogenic fluid; a transfer conduit having one end dipping below the minimum level of liquid in the container and having its other end connected to a heat-dissipating load, the conduit being so constructed as to transmit sufficient heat through its walls to vaporise some of the liquid flowing along it to form a two-phase mixture of liquid and gas; means for causing the liquid flow from the container through the transfer conduit towards the load, and a jacket enclosing at least that part of the transfer conduit which is adjacent to the container, the jacket being connected at one end to the load to receive the gas phase of the cryogenic fluid so that that part of the transfer conduit is shrouded from the atmosphere by a stream of dry gas.

2. The cooling system claimed in claim 1, in which the jacket is in communication with the atmosphere through a control valve at that end which is remote from the said load.

3. The cooling system claimed in claim 1, in which the container has connected to it two additional conduits, one being for the delivery of liquid cryogenic fluid and the other being for the exhaust of gaseous cryogenic fluid.

4. The method of transferring cryogenic liquid through a conduit connecting a supply source of the liquid with apparatus in which the liquid is vaporised by heat for the performance of work, which comprises: causing the liquid to flow from the supply source into the apparatus; discharging the gas generated in the apparatus by passing it to atmosphere as a confined stream shielding and surrounding the liquid transfer conduit in heat exchange relation therewith; vaporising a portion of the liquid in the transfer conduit by heat derived solely from the surrounding exhaust gas stream; and selectively regulating the flow rate of discharge of the shielding gas to the atmosphere whereby to correspondingly regulate the extent of liquid vaporisation in the transfer conduit.
